DAM

Filed July 13, 1926

INVENTOR

Fred A. Noetzli

UNITED STATES PATENT OFFICE.

FRED A. NOETZLI, OF LOS ANGELES, CALIFORNIA.

DAM.

Application filed July 13, 1926. Serial No. 122,141.

This invention relates to the construction of concrete and masonry dams, and the primary object of the invention is to provide a dam of this type which will be less expensive and which can be built in a shorter period of time than dams such as heretofore constructed.

Most concrete and masonry dams as heretofore constructed have been of the gravity, 10 arch, multiple arch or deck slab type. Some of these dams depend for stability upon the weight of the structure alone, such as gravity dams. Others, like arch and multiple arch dams, depend upon arch action, and in deck 15 slab dams the water pressure is supported by slab or beam action.

In both multiple arch and deck slab dams the water pressure is transmitted by means of arches or deck slabs upon buttresses. This 20 transmission of stresses involves arch action or bending moments which may introduce large stresses in the deck and necessitates, in some cases, the use of reinforcing steel for taking care of tension stresses. The decks of 25 these dams are usually thin and are subject to deterioration from frost action.

The objects of my invention are, first, to build a dam which in principle is a gravity dam and in which the parts of the dam in contact with the water in the reservoir are not 30 subject to arch stresses or lateral bending moments and corresponding stresses; second, to build such a dam of a combination of buttress walls and enlarged buttress heads by means 35 of which the water pressure is supported by compression and shear stresses without involving arch action or bending moments in a direction substantially perpendicular to the buttress; third, to build a dam composed of 40 buttresses of the type described which are substantially independent of each other but which form a continuous surface towards the water side from one side of the canyon to the other; fourth, to build a dam for which 45 the sliding factor in horizontal planes is closely regulated by a definite inclination of the up-stream face of the dam.

In the accompanying drawing in which my improved dam is illustrated, Figure 1 is 50 a typical side elevation of a buttress;

Figure 2 is a typical horizontal section through two adjacent buttresses;

Figure 3 is a typical section through the buttress head illustrating the manner in 55 which the pressure of the water in the reservoir

is transmitted by means of the buttress head to the buttress wall;

Figure 4 is a typical section through the buttress head a short distance above the foundation;

Figure 5 is a typical section of the buttress head near the crest of the dam where the water pressure is relatively small.

Referring to Figure 1: The dam shown 60 comprises buttresses B, said buttresses having an enlarged buttress head 6 towards the water side of the buttress wall 7. The buttresses are supported by the foundation material 8. The up-stream face 9 of my improved dam preferably has a variable slope similarly as shown 70 on Figure 1. The slope at the various elevations of the dam may be determined mathematically in the following manner and will result in a relative minimum of concrete being involved in a dam of this type.

Current practice of dam design requires 75 that the sliding factor in horizontal planes at any elevation of the dam must not exceed a certain permissible value of, say, 0.75. The sliding factor f of a dam is equal to the horizontal water pressure H divided by the sum of the weights of the dam D and of the water V overlying the dam.

This relation is expressed by the formula—

$$\text{Sliding factor } f = \frac{H}{D + V}$$

The larger the sliding factor is for values of f less than 1.0, the less concrete in general 90 there will be in a dam of the character described in this specification. However, present practice limits the sliding factor to a value of $f=0.75$. Either by an analytical method, or by cut and trial, I determine the up-stream slope of my dam so that the sliding factor is as close to the value of $f=0.75$ 95 as practicable. For certain foundation conditions, a sliding factor of $f=0.65$ may be all that is permissible while for very good foundation rock a value of $f=0.80$ or more, 100 may be practicable. For each sliding factor there will therefore be a fairly definite up-stream slope, provided that the other conditions relative to the buttresses, such as permissible maximum stresses, in the concrete, 105 etc., be approximately the same.

In the uppermost part of my improved dam the up-stream slope may be nearly vertical, the weight of the concrete being sufficient to 110 make the sliding factor of a size of not more

than 0.75. At the lower elevations the up-stream face is preferably inclined just a sufficient amount to add enough water load to the weight of the dam above the horizontal section investigated to give the sliding factor the desired value.

For a permissible sliding factor of 0.75 and for a span $1=60$ ft. on the water side of the buttress head 6, the up-stream slope of my 10 dam may be practically vertical in the upper 50 ft. of the dam. One hundred feet or more below the crest the slope may be approximately 6 horizontal to 10 vertical. For a 15 smaller sliding factor, the up-stream slope will be flatter, for a larger sliding factor it will be steeper. For different spans 1 of the 20 buttress head 6, the up-stream slope of the dam will also be different from the above one but a fairly definite law will hold for each value of the span 1 and a corresponding size of the buttress head.

There will be stiffeners 10 and an abutment wall 11, if necessary, for each buttress wall to provide for safe column action and to prevent 25 the buttress walls from buckling. The thickness of the buttress walls may be determined in such a manner that the pressure of the water, which pressure is transmitted through the buttress head upon the buttress wall, corresponds 30 approximately to the maximum permissible unit compression stress in the concrete of the dam. In general, this pressure is between 400 and 500 lbs. per square inch. The length of the buttress and the corresponding 35 down-stream slope of the same are then determined according to well-known methods of statics. At the upper elevations of the dam the buttress walls are given a practical minimum thickness regardless of the value of the water pressure.

The buttress head 6 has a substantially constant length 1 along the face of the dam. As the buttress wall 7 is ordinarily thicker at lower than at upper elevations of the dam, 45 the buttress head 6 extends laterally a lesser amount beyond the buttress wall 7 at lower than at upper elevations of the dam.

In case that it is desired to spill the surplus waters in the reservoir directly over the dam, 50 a down-stream slab 12 of reinforced concrete is provided between the buttress walls 7. The slab 12 may be of sufficient thickness and strength to support between the buttresses its own weight and the weight of the water over-flowing the dam. Otherwise, it may be supported by beams 13 resting on the buttress walls 7 or the abutment walls 11.

Fig. 2 shows a horizontal section through the dam along the line 2-2 of Fig. 1. The 60 buttress head 6 is shown curved toward the water side with a radius R . The central angle α of the arc of the buttress head 6 gives a safe and very economical shape of the buttress head for values of α lying between 60° and 90°. The angle α should be about 90°

for relatively low dams and may be nearer 60° for relatively high dams. The buttress head may also be rounded as shown at N of Fig. 2. The average angle α , also in this case is preferably substantially between the values of 60° 70 and 90° both from the point of view of economy and safety. At the junction between two buttress units there may be additional concrete material 14 cast integrally with the buttress head 6 for the purpose of providing a 75 greater thickness of concrete against the water and thus increase the impermeability of the dam. In general, the cross section of the concrete material 14 is larger at lower elevations than at upper elevations of a dam. 80 There is no direct structural connection on the water side between two adjacent buttresses. The junction between two buttresses serves as an expansion joint J. In order to make this joint watertight, I provide a flexible copper water stop 20 or other suitable means for preventing the water in the reservoir from escaping through the joint J.

There may be drainage holes 15 in the buttress heads 6 for carrying off seepage water. 90 In case of a practically impervious bedrock and a first class quality of concrete these drainage holes may be omitted. In order to increase the stiffness of the buttress walls 7 they may comprise two separate walls 7' 95 which are braced by cross walls 16 between walls 7' for stiffening purposes.

Referring now to Fig. 3, a typical section through the buttress head 6 is shown along the line 3-3 of Fig. 1. The arrows z indicate the direction of the water pressure upon the curved surface of the buttress head 6. The arrows z point to the center C of the arc of the curved face of the buttress head 6, and the water pressure upon the individual elements a of the arch is transmitted by direct radial compression in the direction of C upon the buttress wall 7. The up-stream face of the buttress head 6 is symmetrical to the center line C-C of the buttress wall 7. There 105 are therefore no bending moments or arch stresses produced in the buttress head 6, thus giving a direct and therefore statically well determined transmission of the water pressure upon the buttress wall 7. All uncertainties as to arch or bending stresses are thus 110 eliminated.

Referring now to Fig. 4, a typical section through the buttress head 6 is shown along the line 4-4 of Fig. 1 a short distance above the foundation of the dam. The concrete of the buttress head will shrink after pouring and expand or contract under the influence of water soaking or drying out and on account of changes of the temperature. If the span 125 1 is considerable, vertical cracks e might occur in the buttress heads and endanger the safety of the structure. If the span 1 is more than 50 or 60 feet, I provide sliding and expansion areas 17 on one or both sides of the 130

buttress heads 6 preferably a short distance above the foundation, such as shown in Fig. 4. The areas 17 may lie either in approximately horizontal planes, or perpendicularly to the up-stream slope of the dam, if desired. The areas 17 are coated with asphaltum or other suitable material to prevent bonding of the concrete and to facilitate the minute movements due to the expansion and contraction 10 of the concrete of the buttress head 6 in the direction of the span 1. The length l_1 is determined in such a way that the length l_1 of the contiguous portion of the buttress head 6 is not more than 50 or 60 feet, and preferably 15 less. Experience has shown that a body of concrete of less than 50 feet length is much less liable to produce shrinkage cracks e than a body of concrete of greater length.

Referring now to Fig. 5, a typical section 20 through the buttress head 6 is shown along the line 5—5 of Fig. 1. For some distance below the crest of the dam the water pressure is relatively small and the quantity of concrete in the buttress head 6 with a circular up-stream 25 face is relatively too large for an economical transmittal of the water pressure to the buttress wall 7. Some economy may be effected by making the up-stream face of the buttress head 6 three-centered or straight, as shown in 30 Fig. 5. In any case the shape of the buttress head 6 should preferably be such that the lines of pressure on areas a of the buttress head 6, which are symmetrical to the center line $C_1—C_2$ of Fig. 5, intersect in points P 35 which lie on the center line $C_1—C_2$ of the buttress wall 7.

In constructing my improved dam I build buttress heads 6 of curved contour integrally with buttress walls 7 in more or less continuous horizontal layers from the foundation 40 up. I provide an open expansion joint J between each two adjacent buttresses and make this joint water-tight by suitable means. On a rock foundation with fissures I provide 45 drain holes 15 from the rock up through the buttress heads 6. The up-stream slope of the dam may be irregular, for instance, as shown in Fig. 1. Otherwise it may be straight.

I claim:

50 1. A dam comprising a buttress wall and a buttress head supporting the water pressure certain portions of said buttress head extending laterally on both sides of said buttress wall, said buttress head having such a contour on the water side that said water pressure is transmitted by said buttress head upon 55 said buttress wall by direct compression.

60 2. A dam comprising a buttress head and a buttress wall said buttress head having an up-stream face of curved contour, a horizontal plane through said buttress head intersecting said up-stream face on a curve of substantially circular shape, the center of said curve lying substantially on the center line of said 65 buttress wall.

3. A dam comprising a buttress wall and an enlarged buttress head, said buttress head having an up-stream face of curved contour, a horizontal plane through said buttress head intersecting said up-stream face on a curve of 70 substantially elliptical shape.

4. A dam comprising a buttress wall and a buttress head, said buttress head comprising an up-stream face of curved contour, certain parts of said face extending laterally on both 75 sides of said buttress wall, and a drainage well in said buttress head.

5. In a dam the combination of a buttress wall with a buttress head having a face of 80 curved contour, said buttress head comprising concrete material added to the same on the sides and near the up-stream side of said buttress head, whereby the thickness of certain parts of said buttress head is increased near 85 said up-stream side.

6. In a dam the combination of a buttress wall with a buttress head having an up-stream face of curved contour, certain parts of said 90 buttress head projecting sideways beyond said buttress wall.

7. In a dam the combination of a buttress wall with a buttress head having an up-stream face of curved contour, the shape of said up-stream face being such that the water pressure acting upon the up-stream face of said 95 buttress head is transmitted to said buttress wall without involving arch action and lateral bending moments in said buttress head.

8. In a concrete dam the combination of a buttress wall and a buttress head, certain parts of said buttress head extending laterally beyond said buttress wall, with an up-stream face of said buttress head of such shape that the water pressure is transmitted by said buttress head onto said buttress wall 100 in such a manner that no bending moments and arch stresses are produced in a lateral direction in said parts of said buttress head extending laterally beyond said buttress wall.

9. In a dam the combination of buttress walls and buttress heads having an up-stream slope, said up-stream slope being substantially vertical in the upper portions of said dam, and in said lower portions being substantially 110 within the limits of five horizontal to ten vertical, and of seven horizontal to ten vertical, said buttress heads having such a contour on the water side that the pressure of the water in the reservoir is transmitted by said buttress heads upon said buttress walls by direct compression and without involving arch action or bending in a lateral direction.

10. In a dam comprising a plurality of buttresses, the combination of buttress walls and buttress heads having an up-stream face of curved contour, certain parts of said buttress heads at any elevation projecting laterally beyond corresponding parts of said buttress walls at the same elevation, said parts of said buttress heads at lower elevations of 120 125 130

said buttresses projecting laterally a smaller amount beyond said buttress walls than corresponding parts of said buttress head at upper elevations.

5 11. In a dam comprising two adjoining buttresses, the combination of buttress walls with buttress heads having an up-stream face of curved contour, said buttress heads of said adjoining two buttresses having a substantially vertical area of substantially loose contact, said area of contact forming a joint substantially midways between said two adjacent buttresses.

12. In a dam comprising two adjoining 15 buttresses, the combination of buttress walls with buttress heads having an up-stream face of horizontally curved contour, a vertical joint between said buttress heads being located substantially midways between said 20 buttress walls, and means for making said joint water tight.

13. A dam comprising a plurality of buttresses, said buttresses having buttress heads of a contour curved in a horizontal direction, 25 said buttress heads being joined loosely substantially midways between said buttresses, the up-stream faces of said buttress heads forming one contiguous surface toward the water side of said dam.

30 14. In a dam the combination of a plurality of buttresses comprising buttress heads having an up-stream face of curved contour, certain parts of said buttress heads projecting sideways beyond said buttress walls, said

buttress walls having abutment walls near 35 the down-stream ends, and a slab extending between the abutment walls of two adjoining buttresses for facilitating of the spilling of the surplus waters in the reservoir over the 40 dam.

15. In a concrete dam the combination of a plurality of buttresses comprising adjacent buttress heads having a face curved in a horizontal direction and having an area of contact between two adjacent buttress heads, 45 with concrete material added to said buttress heads for the purpose of increasing the area of contact between said buttress heads.

16. A dam comprising a buttress wall and a buttress head certain parts of which are 50 projecting laterally beyond said buttress wall, a joint in the parts of said buttress head projecting beyond said buttress wall, and suitable material in said joint for preventing bonding of the concrete in the joint and for 55 facilitating lateral expansion and contraction of said buttress head.

17. A dam comprising a buttress wall and a buttress head, certain parts of said buttress head projecting laterally beyond said buttress wall, a joint in said parts of the buttress head tending to decrease the length of the 60 solid portion of said buttress head near said joint to not more than 50 to 60 feet measured in a direction perpendicular to said buttress 65 wall.

FRED A. NOETZLI.
